THERMOPLASTIC LABEL DISPENSER

Ernest L. Kallander, Framingham, Mass., assignor to Dennison Manufacturing Company, Framingham, Mass., a corporation of Massachusetts

Application October 22, 1938, Serial No. 236,597

4 Claims. (Cl. 263—7)

While the present invention relates particularly to devices for dispensing thermoplastic labels, that is labels coated with material which must be heated to be tacky, in some of its aspects the invention is applicable to devices for dispensing any kind of labels or other slips.

The principal objects of the invention are to provide a device of the character referred to which is simple and economical in construction, which is reliable and durable in operation, which is readily portable and which can be easily operated by hand. In its more specific aspects the objects of the invention are to provide a device which receives labels in any form and delivers them in tacky form, which makes the labels tacky without applying liquid to them and which does not tend to become gummed.

In one aspect the invention involves a turntable having an upper surface for supporting labels with their gummed sides uppermost in combination with means for depositing labels of said surface in spaced relation to each other and means for heating the labels while on the turntable. The turntable is preferably rotated step by step so that the operator can pick up a label each time the table comes to rest. By controlling the rotation of the table with a handle located adjacent the label feeding means, a single operator can conveniently attend both to the label supply and the rotation of the table. In the preferred form of the invention the turntable comprises a perforate sheet with stationary heating means under the sheet, whereby the labels may be quickly heated without rotating the heating means with the table.

In another aspect the invention involves an elevator for lifting a stack of labels and means above the stack engageable with the top label for limiting the upward movement of the elevator and transferring the top label from the stack, this means preferably comprising a friction roller for sliding the top label off the stack and means for preventing the underneath labels from sliding with the top label. By suitably interconnecting the label transfer means and the turntable in timed relationship the labels may be deposited on the turntable in spaced relationship so that they may be readily picked up by the operator after they become tacky.

For the purpose of illustration a typical embodiment of the invention is shown in the accompanying drawings in which

Fig. 1 is a top plan view with parts broken away;

Fig. 2 is a side elevation with parts broken away;

Fig. 3 is a section on line 3—3 of Fig. 1;

Fig. 4 is an end elevation with parts broken away;

Fig. 5 is a section on line 5—5 of Fig. 4;

Fig. 6 is a section on line 6—6 of Fig. 4;

Fig. 7 is a vertical central longitudinal section of the label-feeding means with parts omitted; and

Fig. 8 is a sectional view taken on the line 8—8 of Fig. 2, parts being broken away.

The particular embodiment of the invention chosen for the purpose of illustration comprises a base 1, provided with four upstanding posts 2 upon the upper ends of which is mounted a cup-shaped casting 3, the posts 2 being secured to the base 1 and the casting 3 by means of screws 4. As shown in Fig. 3 the casting 3 is provided with a central opening surrounded by a hub 5 in which is rotatably mounted a turntable comprising a perforated disk 6 whose periphery rests upon the peripheral flange 7 of the casting 3, a pivot pin 8 having an enlarged upper end 9 fitting in the opening in the boss 5, a reinforcing disk 10, a ratchet wheel 11 and screws 12 for securing the rotating parts together. A series of electric heating elements 13 are mounted in the cup-shaped casting 3 by means of straps 14 and screws 15, the casting being provided with openings 16 to accommodate the binding posts 17 to which current is supplied through a cable 18 and a switch 19 which is preferably of the three position type, connecting all of the heating units in circuit in one position for quick heating, connecting a lesser number of heating units in circuit in another position for medium heating and connecting a still smaller number of heating units in circuit in another position for low heat.

The mechanism for supplying labels to the turntable comprises an elevator platform 20 for carrying an inclined stack of labels L (Figs. 1 and 7). The platform 20 is mounted on a cross-bar 21 which in turn is mounted in the arms 22 of a bracket 23 by means of pins 24 fast in the ends of bar 21 and projecting through slots 25 in the arms 22. The bracket 23 is pivotally mounted on the base at 26 and has an integral extension 27 to carry an adjustable counter-weight 28 to cause the elevator to lift the stack of labels against the feed roller 30 (Fig. 7) and the stationary stop 31 (Figs. 1 and 2). Mounted on the base 1 at one end of the platform 20 is a pair of inclined bars 32 which provide a guideway 33 therebetween. As shown in Fig. 8 the

- end of the bar 21 projects through this guideway 33, the end of the bar being reduced in cross-section with the sides of the reduced portion inclined at the same angle as the bars 32 to fit 5 against the opposite sides of the guideway 33. Thus, as the elevator 20 rises it is maintained in a horizontal position by the end of the bar 21 fitting in the guideway 33, the pins 24 sliding in the slots 25 to permit the bracket 23 to swing about the pivot 26 while the elevator 20 moves in a straight line parallel to the inclined bars 32. Mounted on the platform 20 by means of screws 35 are adjustable angle bars 36 to confine the inclined stack of labels on the elevator.
- 16 Referring particularly to Figs. 2 and 7 the cup-shaped casting 3 has a pair of depending lugs 37 adjacent the elevator for supporting a wedge-shaped metal block 38 through the medium of screws 39 extending through the lugs 37 and thence into the block 38. The outer inclined face of the block 38 is provided with a dovetail guide 40 (Figs. 2 and 4) in which is slidably mounted a wooden block 41. The block 41 is yieldingly urged upwardly along the dovetail guideway by 25 means of a spring 42 and the upward movement of the block is limited by an adjusting screw 43 threaded through a post 44 mounted on the block 41, a lock nut 45 being provided to hold the screw 43 in adjusted position. As shown in Fig. 7 the upper end of the block 41 carries a felt pad 42 which has a rounded nose disposed adjacent a second feed roller 50. The rollers 30 and 50 are preferably formed of moderately soft rubber or other material which affords considerable friction. Thus when the rollers 30 and 50 are rotated in the direction of the arrows in Fig. 7 the top label is slipped off the stack and projected onto the turntable 6 at the approximate position indicated at L' in Fig. 7, the felt shoe 42 serving 35 to prevent the underneath labels from sliding off the stack with the top label.
- 40 The mechanism for actuating the turntable 6 and the rollers 30 and 50 comprises an arm 51 provided with a hub 52 fitting over the smaller lower end of the pins 8, the hub being supported by a member 53 suitably secured to the lower end of the pin 8. As shown in Fig. 1 the arm 51 carries on its upper surface a pawl 54 which is held in engagement with the ratchet wheel 11 by means 45 of a spring 55. Pivotedly connected to the arm 51 at 56 is a rod 57 sliding in a guide 58 which is secured to the under side of the casting 3. The outer end of the rod 57 is provided with a handle 59 with which the rod may be pushed inwardly, the spring 60 returning the rod to its position shown in Fig. 1. Pivotedly connected to the arm 51 at 61 is a link 62, the other end of the link being pivotally connected to a sleeve 63 55 slidable on rod 64 which reciprocates back and forth in the guide lugs 65 fast to the bottom of the casting 3. The sleeve 63 is free to slide back and forth on the rod 64 between a fixed stop 67 and an adjustable stop 68, whereby the rod 64 may be moved back and forth by the sleeve more or less depending upon the position of the stop 68 on the rod. At the right-hand end the rod 64 is provided with teeth to form a rack 70 for rotating the rollers 30 and 50 through the following mechanism.
- 60 Journaled in bearings fast to the main frame casting 3 are four shafts 71, 72, 73 and 74, the latter two carrying the rolls 30 and 50 respectively. Fast to the shaft 71 is a gear 81 meshing with the rack 70. Also fast to the shaft 71 65 is an arm 82 carrying a spring-pressed pawl 83

(Fig. 6). Loosely rotating on the shaft 71 is a gear 84 and fastened to the front side of the gear by means of screws 85 is a ratchet wheel 86 engaged by the pawl 83. Meshing with the gear 84 is a gear 87 fast to shaft 72, and fast to the shaft 73 is a gear 88. The shaft 72 also carries a gear 89 meshing with gear 90 on shaft 74. Thus when the rack 70 moves to the left the roll 30 is rotated through gear 81, pawl 83, ratchet 86, gear 84, gear 87, gear 88 and shaft 73. At the same time the roller 50 is rotated through the same train of mechanism up to the gear 87 and thence through shaft 72, gear 89, gear 90 and shaft 74. Thus the two rollers 30 and 50 rotate in unison, either at the same peripheral speeds 15 or preferably with roller 50 rotating at a slightly greater speed. To adjust the extent of rotation of the rollers 30 and 50 for each operation, to suit different sizes of labels, the adjustable stop 68 is adjusted back and forth on the rod 64 to vary 20 the extent of reciprocation of the rack 70, thereby to vary the number of teeth on the ratchet wheel 86 over which the pawl 83 ratchets each time the rack 70 moves to the right.

Disposed over the turntable is a hood 91 removably secured to the base 4 by means of wing nuts 92 (Fig. 1), the hood preferably covering all of the turntable except a limited area accessible through the opening 93 near the handle 59 which affords access to the labels after they have traveled almost 360° around the axis of the turntable.

From the foregoing it will be evident that upon pressing inwardly upon the handle 59 of the plunger 57 the turntable is rotated one step 35 counterclockwise through the medium of the arm 51, pawl 54 and ratchet wheel 11. At the same time the arm 51 moves the rack 70 to the left thereby rotating the rollers 30 and 50 sufficiently to project the topmost label from the stack of 40 labels to the turntable. By suitably adjusting the driving mechanism the labels may be deposited on the turntable in spaced relationship in contradistinction to touching or overlapping relationship, thereby to make it easier for the 45 operator to pick the labels one by one off the turntable as they come around to the operator's position adjacent the handle 59. As the labels are projected from the top of the stack the elevator gradually rises under the influence of the 50 weight 28 until all of the labels have been delivered to the turntable. To refill the machine the platform is depressed to the position shown in Fig. 2 and a new stack of labels is placed on the platform. By inclining the stack relative to the 55 platform 20 the labels have less tendency to stick together, particularly in the case of embossed labels.

It should be understood that the present disclosure is for the purpose of illustration only 60 and that this invention includes all modifications and equivalents which fall within the scope of the appended claims.

I claim:

1. Apparatus for dispensing thermoplastic labels comprising a turntable having an upper surface for supporting labels with their gummed sides uppermost, means for rotating said turntable, means for depositing labels on said surface in spaced relation to each other, and means for heating the labels while on the turntable.

2. Apparatus for dispensing thermoplastic labels comprising a turntable having an upper surface for supporting labels with their gummed sides uppermost, means for rotating said turn- 75

table step by step, means for depositing a label on said surface each time the turntable is advanced one step, and means for heating the labels while on the turntable.

3. Apparatus for dispensing thermoplastic labels comprising a turntable having an upper surface for supporting labels with their gummed sides uppermost, means for rotating said turntable step by step, a handle at one side of the turntable for controlling said rotating means, means adjacent said handle for depositing a label on said surface each time the turntable is ad-

vanced one step, and means for heating the labels while on the turntable.

4. Apparatus for dispensing thermoplastic labels comprising a turntable having a perforated surface for supporting labels with their gummed sides uppermost, means for rotating said turntable step by step, means for depositing a label on said surface each time the turntable is advanced one step, and stationary means under said surface for heating labels while on the turntable.

ERNEST L. KALLANDER.
